UNITED STATES PATENT OFFICE.

THOMAS WALTER BARBER, OF LONDON, ENGLAND.

PRINTING-PRESS.

No. 833,018.

Specification of Letters Patent.

Patented Oct. 9, 1906.

Application filed November 13, 1905. Serial No. 287,130.

To all whom it may concern:

Be it known that I, THOMAS WALTER BARBER, a subject of the King of England, residing at Westminster, London, England, have invented certain new and useful Improvements in Printing-Presses, of which the following is a specification.

This invention relates to improvements in printing-presses, and is particularly applicable to the type of apparatus described in my previous United States patent, No. 795,785.

In apparatus of that type the valves of the driving-motor are operated automatically at or near the ends of the stroke by the engagement of an operating-lever with fixed stops. It is found that when the motor is driven very slowly (say for cleaning purposes) the momentum of the carriage may not be sufficient to bring about complete operation of the valves, so that the motor is brought to rest.

The objects of this invention are to avoid such accidental stoppage and to provide an efficient means for operating the valves of the carriage-motor.

According to this invention an auxiliary motor actuated by the exhaust from the main carriage-motor is employed to insure the operation of the valves. This auxiliary valve-motor may comprise a double-acting cylinder communicating with the exhaust-valves of the main carriage-motor, and the mechanically-operated inlet and exhaust valves of the main carriage-motor are operatively connected—say by links—with the piston of the auxiliary valve-motor.

To set the auxiliary valve-motor in operation when the carriage reaches or approaches either end of the stroke, a pilot-valve may be mechanically opened to admit a portion of the exhaust fluid from the carriage-motor to one end of the valve-motor. For this purpose the exhaust-valves may be of the rotary type comprising two concentric sleeves with suitable orifices, one of the sleeves being automatically rotated by the movement of the carriage—say by a projecting arm and fixed stop—and the other sleeve being rotated by the valve-motor.

In order to vary the stroke of the carriage-motor, stops may be arranged at different points in the length of the press and may be carried on concentric spindles having handles attached thereto, so that any one stop may be brought into the path of the valve-operating arm.

In the accompanying drawings, Figure 1 is

a longitudinal section of a portion of a printing-press constructed in accordance with this invention. Fig. 1^a is a continuation of Fig. 1, showing the left-hand end or remaining portion of the press. Fig. 2 is a side elevation of the valves and valve-operating gear alone, partly in section; and Fig. 3 is an end elevation of the press, partly in section.

Like letters indicate like parts throughout the drawings.

The carriage A is mounted to reciprocate on the frame B. The double-acting fluid-pressure cylinder C is attached to the under side of the carriage and provided with a piston D and piston-rods D', attached to the frame B of the press. At each end of the cylinder C are the exhaust-valve E and inlet-valve F.

The inlet-valves F communicate through telescopic or flexible conduits G with a supply of acting fluid, such as compressed air. In the form shown each inlet-valve comprises a slotted sleeve F', rotatable in the valve-chest. A short crank or arm F² is attached to the sleeve, and the movement of the crank or arm brings the slot in the sleeve F' opposite or away from the cylinder-port F³.

Each exhaust-valve E comprises two concentric sleeves K and L, rotatable in the valve-chest. The outer sleeve K has a narrow slot K' and a wide slot K². Within this is an inner sleeve L, having one slot L' constituting the pilot-valve. The outer sleeve K carries a lever K³, and the inner sleeve has a short arm L². Normally the narrow slot K' is opposite the outlet and the slot L' does not coincide therewith.

The exhaust-valves E communicate, through conduits H, with the two ends of a small auxiliary cylinder J, supported by the main cylinder C. The cylinder J has an exhaust-outlet J' midway of its length. Within the cylinder is a piston J², having a piston-rod J³ at each side. When exhaust-gas from the cylinder C enters the auxiliary cylinder J at either end, the piston J² is suddenly blown over to the opposite end. When the piston J² has passed the exhaust-outlet J', it completes its stroke, owing to the momentum of the moving parts and to the fact that the whole exhaust from the cylinder C is being discharged through the auxiliary cylinder J behind the piston J², and the exhaust-outlet J' is made sufficiently small to maintain pressure behind the piston J² momentarily after it has passed the exhaust-outlet J'.

Each piston-rod J^3 is connected by a link J^4 to the lower end of one lever K^3 , and the other end of the lever K^3 is connected by a rod M with the inlet-valve crank or arm F^2 at the opposite end of the cylinder, so that the movement of the piston J^2 shifts both the exhaust-valve sleeves K and the inlet-valve sleeves F' . The crank or arm F^2 may be slotted at F^4 , so that the opening of the inlet-valve does not take place until the corresponding exhaust-valve is closed.

Mounted on the frame of the press B is a support N , carrying three stops $O P Q$ on three concentric rotatable spindles $O' P' Q'$, having handles $O^2 P^2 Q^2$ attached thereto. By turning any one of these handles through a right angle the corresponding stop can be brought into the path of the short arm L^2 of the exhaust-valve at that end of the cylinder, so as to turn the sleeve L . The sleeves L being embraced by the sleeves K and frictionally engaging therewith are turned when the sleeves K turn. The limiting closed position of the sleeve L is shown on the left hand in Fig. 2, and the limiting open position of the sleeve L is shown on the right in Fig. 2. The sleeve L cannot move beyond its limiting positions.

The operation of the apparatus is as follows: One of the stops $O P Q$ having been turned into the path of the arm L^2 at each end of the press, according to the length of stroke required, fluid is admitted to one end of the cylinder, which commences to move. As it approaches the end of its stroke, say the left-hand end, the arm L^2 strikes the stop and is shifted over so as to bring the slot L' opposite the slot K' , thus opening the pilot-valve and permitting a certain quantity of exhaust fluid to pass from the cylinder C , through the conduit H , to the cylinder J . The piston J^2 is thus blown over to the other end of the cylinder J —i. e., to the right—and the levers K^3 are moved by it to the right. The sleeve K (on the left) is thus turned to bring the wide slot K^2 opposite the slot L' , and the exhaust-valve is then fully open. At the same time the other exhaust-valve (on the right) is closed, the upper end of the lever K^3 (on the left) pulls the rod M , and when the latter reaches the end of the slot F^4 it opens the inlet-valve F at the other end of the cylinder (on the right) and the inlet-valve, (on the left,) which has been opened, is closed. Thus during the whole or the early part of each stroke the inlet-valve F is opened to the acting end of the cylinder C , while the idle end of the cylinder C is opened to exhaust through the conduit H and the outlet J' .

This invention has been described in its application to the particular printing-press forming the subject of my previous patent above mentioned, but it is equally applicable to any other form of printing-press in which

the valves of the carriage-motor are operated by the movement of the carriage itself.

It is to be understood that the details of construction and arrangement may be varied without departing from this invention. For example, slide-valves or drop-valves may be used in place of the rotary valves shown. Also the exhaust-valves instead of having two operating-levers may have one operating-lever, which at low speeds may be moved slightly by the stop to open the valve to a certain extent, when the auxiliary motor will be brought into play to complete the movement.

What I claim as my invention, and desire to secure by Letters Patent, is—

1. In a printing-press the combination of a reciprocating carriage, a double-acting fluid-pressure motor operatively connected therewith and having inlet and exhaust valves, an auxiliary motor actuated by the exhaust from the carriage-motor and operatively connected with the inlet and exhaust valves to insure their movement and means actuated by the movement of the carriage for admitting exhaust to the auxiliary motor.

2. In a printing-press the combination of a reciprocating carriage, a double-acting fluid-pressure motor operatively connected therewith and having an inlet and an exhaust valve at each end, an auxiliary motor communicating at its ends respectively with the two exhaust-valves, means actuated by the movement of the carriage for admitting a fraction of the exhaust from the carriage-motor to the auxiliary motor, and operative connections between the auxiliary motor and the main exhaust and inlet valves to insure their movement.

3. The combination with a printing-press of a reciprocating carriage, a double-acting fluid-pressure motor operatively connected therewith, an inlet-valve and an exhaust-valve at each end of said motor, an auxiliary motor communicating at its ends respectively with the two exhaust-valves, each exhaust-valve comprising two operative parts constituting a pilot exhaust-valve and a main exhaust-valve, means for operating the pilot-valve by the movement of the carriage, and operative connections between the auxiliary motor and the main exhaust-valves and inlet-valves to insure their movement.

4. The combination with a printing-press of a reciprocating carriage, a double-acting fluid-pressure motor operatively connected therewith, an inlet-valve and an exhaust-valve at each end of said motor, an auxiliary motor communicating at its ends respectively with the two exhaust-valves, each exhaust-valve comprising two operative parts constituting a pilot exhaust-valve and a main exhaust-valve, means for operating the pilot-valve by the movement of the carriage, means for varying the point in the movement of the carriage at which each pilot-

valve is operated, and operative connections between the auxiliary motor and the main exhaust-valves and inlet-valves to insure their movement.

5. In a printing-press the combination of a press-frame, a carriage mounted to reciprocate thereon, a main fluid-pressure cylinder secured to said carriage, a piston in the cylinder connected to the press-frame, an inlet-valve and an exhaust-valve at each end of said cylinder, a double-acting auxiliary cylinder secured to the main cylinder, a piston in that auxiliary cylinder, a central outlet from that cylinder, a conduit from each exhaust-valve to one end of the auxiliary cylinder, and operative connections between the piston and the auxiliary cylinder and the main inlet and exhaust valves.

6. In a printing-press the combination of a press-frame, a carriage mounted to reciprocate thereon, a main fluid-pressure cylinder connected to said carriage, a piston in the cylinder connected to the press-frame, a rotary inlet-valve at each end of said cylinder, a rotary exhaust-valve at each end of said cylinder, a valve-operating lever operatively connected with each exhaust-valve and the inlet-valve at the opposite end, a double-acting auxiliary cylinder secured to the main cylinder, a piston and piston-rods in that cylinder, a central outlet from that cylinder, a conduit from each main exhaust-valve to one end of the auxiliary cylinder, and a link connecting each main-valve-operating lever with the auxiliary piston-rod.

7. In a printing-press the combination of a press-frame, a carriage mounted to reciprocate thereon, a main fluid-pressure cylinder connected to said carriage, a piston in the cylinder connected to the press-frame, a rotary inlet-valve at each end of said cylinder, a crank attached to said valve, a rotary exhaust-valve at each end of said cylinder, comprising an outer sleeve having a wide slot and a narrow slot, an inner concentric sleeve having one wide slot constituting with the outer narrow slot a pilot-valve, a projecting arm attached to each inner sleeve, a valve-operating lever attached to each outer sleeve, a link connecting the inlet-valve

crank at each end with the operating-lever at the other end, a double-acting auxiliary cylinder secured to the main cylinder, a piston and piston-rods in that cylinder, a central outlet from that cylinder, a conduit from each main exhaust-valve to one end of the auxiliary cylinder, a link connecting each main-valve-operating lever with the auxiliary piston-rod and a plurality of fixed stops arranged in the path of the arm projecting from the inner exhaust-valve sleeve.

8. In a printing-press the combination with a press-frame, a carriage mounted to reciprocate thereon, a main fluid-pressure cylinder connected to said carriage, a piston in the cylinder connected to the press-frame, a rotary inlet-valve at each end of said cylinder, a crank attached to said valve, a rotary exhaust-valve at each end of said cylinder, comprising an outer sleeve having a wide slot and a narrow slot, an inner concentric sleeve having one wide slot constituting with the outer narrow slot a pilot-valve, a projecting arm attached to each inner sleeve, a valve-operating lever attached to each outer sleeve, a link connecting the inlet-valve crank at each end with the operating-lever at the other end, a double-acting auxiliary cylinder secured to the main cylinder, a piston and piston-rods in that cylinder, a central outlet from that cylinder, a conduit from each main exhaust-valve to one end of the auxiliary cylinder, a link connecting each main-valve-operating lever with the auxiliary piston-rod, a plurality of stops disposed at different points in the length of the press and arranged to be brought into the path of the arms projecting from the inner exhaust-valve sleeves, concentric rotatable spindles mounted on the press-frame and carrying said stops and handles on said spindles.

In testimony whereof I have signed my name to this specification in the presence of two subscribing witnesses.

THOMAS WALTER BARBER.
